(57) **CLAIM**

The ornamental design for an oil bottle, as shown and described.

DESCRIPTION

FIG. 1 is a right side view for an oil bottle showing my new design;

FIG. 2 is a rear view thereof;

FIG. 3 is a left side view thereof;

FIG. 4 is a front view thereof;

FIG. 5 is a rear perspective view thereof;

FIG. 6 is a front perspective view thereof;

FIG. 7 is a top view thereof; and,

FIG. 8 is a bottom view thereof.

The broken lines in Figures depict environmental subject matter for the invention and form no part of the claimed design.

The ACCUCHARGE™ forming part of the claimed design is a registered trademark of K&N Engineering, Inc.
